UNITED STATES PATENT OFFICE.

CLARENCE H. ASHMEAD, JR., OF FORT LAUDERDALE, FLORIDA.

JUMP-SPARK TIMER.

1,180,688.

Specification of Letters Patent.

Patented Apr. 25, 1916.

Application filed February 16, 1915. Serial No. 8,483.

To all whom it may concern:

Be it known that I, CLARENCE H. ASHMEAD, Jr., a citizen of the United States, residing at Fort Lauderdale, in the county of Dade and State of Florida, have invented certain new and useful Improvements in Jump-Spark Timers, of which the following is a specification.

My invention relates to jump-spark timers for internal combustion engines wherein friction between the contacting parts and wear thereof is reduced to a minimum.

Further, it is an object of the invention to provide one of the two contacting electrodes rotatable and the other electrode as yieldingly slidable to accomplish the aim set forth. Also, the invention aims to provide a novel construction of supporting and housing means for the electrodes as illustrated in accompanying drawings and hereinafter described.

In said drawings: Figure 1 is a front elevation of the timer with the face plate removed; Fig. 2 is a rear elevation of the timer; Fig. 3 is a cross section on the line 3—3 of Fig. 1, and Fig. 4 is a detail sectional view taken through the slidable electrode and supporting rotor and at a right angle to Fig. 3.

Referring specifically to the drawings A generally represents one of the improved timers. It is clear that any desired number of timers may be employed in connection with an internal combustion engine, depending upon the number of its cylinders. The timer has a rotary shaft 1 which removably extends into a short hollow shaft 2 of a rotor having a head 3 of greater diameter than the collar. A stationary casing 4 has a collar 5 in which the hollow shaft 2 is journaled and has a receptacle 6 in which head 3 is disposed and which receptacle has an annular inclosing wall 7. A plate 8 may extend across the open face of the receptacle and be secured as by screws 9 to the wall 7. The rotor 2—3 rotates with shaft 1 and to this end a collar or ring 10 is mounted on shaft 2 and through the ring and shaft 2, one or more set screws 11 pass to fasten the shaft 1 and rotor rigidly together. Ring 10 abuts the end of collar 5 to prevent undue inward movement of the rotor.

On the head 3 is formed integrally a box 12 open at one end and closed at the other end by a wall 13. Slidably mounted within

the box is an electrode 14 against the inner end of which and the wall 13, an expansion spring 15 bears, serving to project the electrode beyond the open end of box 12. An elongated slot 16 is provided in the electrode and through the same passes a retaining pin in the form of a set screw 17 removably screwed into the box 12.

Electrode 14 wipes a rotatable roller or electrode 12 within receptacle 6 loosely mounted on a stud shaft 19 screwed by a shank 20 through the casing 4. A nut 21 engages the shank 20 interiorly of the casing and nuts 22 engage the shank exteriorly of the casing and clamp between them a conductor wire 23. A bearing 24 for stud 19 may be mounted on plate 8. It will be noted that plate 8 prevents longitudinal displacement of the roller electrode 18.

Electrodes 14 and 18 are properly connected in an electric circuit to cause the production of a jump spark through wiping contact of the electrodes. Shaft 1 may be in the circuit mentioned and is preferably made of conducting material, as is also the rotor 2—3 so as to conduct the current to the electrode 14. Also the nuts 22 and shaft 19 are of conducting material so as to conduct the current to electrode 18. Of the remaining parts, casing 4, cover 8 and ring 10 may be of any suitable material but preferably are of insulating material like vulcanized fiber or hard rubber in order to insulate the conducting parts.

In operation, the rotor and electrode 14 rotate with shaft 1 and during rotation the electrode wipes electrode 18, slides inwardly against the tension of spring 15 and causes electrode 18 to rotate, thus insuring effective contact of the electrodes to close the circuit through the spark plug to provide the jump spark, and at the same time effect such contact practically without friction and wear of the parts.

As merely the preferred embodiment of the invention has been illustrated and described, changes within the spirit and scope may be resorted to.

I claim:

1. A timer having a casing, a rotor therein having a box member overlapping the casing to prevent displacement of the rotor through movement in one direction, an electrode member slidable in said box member, one of said members being provided with an elongated slot, the other of said members be-

- 2
- ing provided with a pin entering said slot, and means to urge said electrode outwardly.
2. A timer having a casing, a rotor there-in having a box member and a shaft, said 5 box member overlapping the casing to prevent displacement of the rotor through movement in one direction, a power shaft, an abutment member separate from the casing and engaging the same and a fastening 10 member extending through the abutment member and coöperating with said shaft to prevent movement of the rotor in the direction opposite to the said direction, electrode means mounted on the casing and electrode 15 means coöperating with said electrode means carried by the box.
3. A timer having a casing, a rotor within said casing, an electrode carried by said rotor, said rotor abutting the casing to prevent 20 movement of the rotor in one direction, a shaft, and means common for the purposes of fastening said rotor to said shaft and preventing movement of the rotor in the direction opposite to that previously specified.
- 25 4. A timer having a casing, an electrode within said casing, a rotor having a head abutting the casing, a box on said head, an electrode to engage said electrode movably mounted in said box, a shaft on said rotor, a second shaft, means mounted on the first shaft abutting the casing and fastening means to secure the shafts in rigid relation 30 passing through said means.
5. A timer having a casing, provided with a receptacle and a collar and a closure plate, a stud in said casing, an electrode rotatably mounted on said stud and mounted against displacement by said plate, a rotor having a shaft mounted in said collar and having a head to overlap and abut the receptacle, a 35 box integral with said head, an electrode slidably mounted in said box, a spring in said box to urge the last mentioned electrode outwardly, a second shaft, a ring mounted on one of said shafts abutting said collar 40 and a fastening member passing through said ring rigidly connecting said shafts.

In testimony whereof I affix my signature in presence of two witnesses.

CLARENCE H. ASHMEAD, JR.
